UNITED STATES PATENT OFFICE.

HORATIO C. RANDALL, OF SAN FRANCISCO, CALIFORNIA; ANNIE LOUISE RANDALL EXECUTRIX OF SAID HORATIO C. RANDALL, DECEASED.

ELEVATOR-CONTROL SYSTEM.

1,347,711.

Specification of Letters Patent. Patented July 27, 1920.

Application filed March 20, 1919. Serial No. 283,852.

To all whom it may concern:

Be it known that I, HORATIO C. RANDALL, a citizen of the United States, and a resident of the city and county of San Francisco and State of California, have invented a certain new and useful Elevator-Control System, of which the following is a specification.

The invention relates to elevator control systems and particularly to systems in which the operation of the car moving motor is controlled by the positions of the elevator shaft door locks.

An object of the invention is to provide means for preventing the operation of the car moving motor when a shaft door lock is unlocked.

Another object of the invention is to provide means for preventing a shaft door from being unlocked while the car moving motor is in operation.

Another object of the invention is to provide means for preventing the operation of the car moving motor until every shaft door is closed and locked.

Another object of the invention is to provide a system of the class described in which only one switch is employed which is held in the open position when any shaft door is unlocked.

The invention possesses other advantageous features, some of which, with the foregoing, will be set forth at length in the following description where I shall outline in full, that form of the invention which I have selected for illustration in the drawings accompanying and forming part of the present specification. In said drawings I have shown one form of the apparatus of my invention, but it is to be understood that I do not limit myself to such form, since the invention, as expressed in the claims, may be embodied in a plurality of forms.

Referring to said drawings:

Figure 1 is an elevation, somewhat diagrammatic, of an elevator shaft having two doors equipped with the apparatus of my invention.

Fig. 2 is a cross section through the door locking means, showing the positions of the parts when the door is locked.

Fig. 3 is a similar cross section showing

the positions of the parts when the door is unlocked.

Fig. 4 is a diagrammatic representation 55 of a portion of the electric control circuit, showing a relay.

Fig. 5 is a diagrammatic representation 60 of one form of connection of the system with a hydraulic motor.

In accordance with my invention when applied to electrically operated elevators, I provide a switch in the circuit of the car moving motor and provide separate means on each shaft door for locking the door in the closed position and provide means operatively connecting the plurality of locking means with the switch so that the switch is opened when any one of the plurality of shaft doors is unlocked and is held open as 65 long as any shaft door is unlocked. In Fig. 1, the shaft door 2 is shown in the locked position and the door 3 is shown unlocked and partly open. Arranged on each door is a bolt 4 which moves into and out of the 75 case 5 as the door is closed and opened. A case 5 is secured to the elevator shaft at each door and the position of the case with relation to the bolt is fixed.

Pivoted within each case 5 is a lever 6 80 having three arms, 7, 8 and 9. The arm 7 extends from the side of the case and the arm 8 projects from the top of the case and is provided with a transversely projecting pin 12. Arranged in the elevator shaft is a 85 vertically movable vertical wire 13 which passes through slots or passages in the ends of the lever arms 7. The wire is suspended by a spring 14 or other yielding support, so that it may be moved vertically and is provided on its lower end with a weight 15, which tends to hold the wire in its lower position. Secured to the wire above each arm 7 is a stop 16 which is engaged by the arm 7 and raised as the arm is raised, that 90 is, the wire is raised when any one of the plurality of arms 7 is raised. Arranged in the circuit 17 of the car moving motor 18 is a switch 20 which is opened when the wire is raised and closed when the wire is lowered. The switch is preferably of the sliding contact type, having the fixed contacts 21 and 22 and the sliding contact 23. Insulating sections 24—25 are arranged at op-

posite ends of the sliding contact so that the motor circuit is broken when the sliding contact moves from the fixed contacts. The sliding contact is preferably attached to the 5 wire adjacent its upper end, such positions possessing the advantage that should the wire break or the weight become detached, the spring 14 would open the switch.

Means are provided for preventing the 10 wire from being raised and consequently preventing any lock from being unlocked, when the car moving motor is in operation. Secured to the wire 13 immediately above weight 15 is a toothed bar 45, slideable 15 in a guideway so that it may not become displaced laterally. Arranged adjacent the toothed bar 45, is a second toothed bar 46 which is movable laterally into and out of engagement with the bar 45, but so mounted 20 that it is substantially immovable longitudinally. Therefore, when the toothed bars are in engagement, the wire 13 may not be moved vertically. Means are provided for moving the bar 46 into engagement with the 25 bar 45 and holding it in such engagement during the time that the motor 18 is energized. As shown in Fig. 1, the bar 46 is mounted on one end of the bell-crank 47 to the other end of which is attached the core 30 48 of the solenoid 49 which is connected across the circuit 17. When the circuit is closed the core is raised and the bar 46 moved into contact with the bar 45. When the circuit is opened, the core falls 35 and pulls the bar 46 out of engagement with the bar 45. Consequently no lock may be unlocked while the motor circuit is closed or when the elevator car is in motion.

The bolt 4 is provided with a notch 26 40 in which the projection 27 on the lever arm 9 seats when the door is fully closed, thereby locking the door in closed position. To open the door, the lever 6 must be moved about its pivot to depress the arm 9 and this 45 motion simultaneously raises the arm 7 and the wire, opening the motor circuit. The lever is moved about its pivot by any suitable means, that shown in the drawings comprising a shoe 28, mounted on the elevator 50 car 29 and movable by the foot button 31 into contact with the pin 12 on lever arm 8. Contact of the shoe with the pin moves the lever about its pivot, raising the wire and unlocking the door.

Means are provided for locking the lever 55 in the position moved to, said lever locking means being arranged to be released by the subsequent locking of the door. Pivotally mounted in the case 5 below the lever arm 9 60 is a weighted latch 32 having a notch 33 therein which engages the pin 34 on the lever arm 9 when the arm is depressed and holds the arm in such position. The latch 32 is released from the arm 9 by contact 65 with the forward end of the bolt 4, the po-

sition of the latch 32 with respect to the notch 26 and projection 27 being such that when the bolt releases the latch 32, the projection 27 moves into the notch 26 locking the bolt in position. When the latch is 70 released from the arm 9, the lever is moved by the pull of the weight 15.

To insure the locking of the lever, a latch lever 45, disposed above the bolt, is provided with a notch 35 which engages a pin 36 on 75 the lever arm 8 when the bolt is withdrawn. When in this position, the lower edge of the latch 34 lies in the path of the bolt 4, so that when the bolt seats in the case, the latch 34 is raised, the lever moved and the 80 projection 27 moved into the notch 26. The case 5 is provided with an aperture through which the bolt passes and the bolt is provided with a bifurcated end which engages a pin 37 in the case. Instead of arranging 85 the switch 20 in the motor circuit, it may be arranged in a local circuit with the relay 38, which is arranged to open and close a switch 39 in the motor circuit, as shown in Fig. 4. The switch 39 may be so connected 90 to the relay that it is opened when the relay circuit is closed or is opened when the relay circuit is opened and consequently the switch 20 may open the relay circuit or close the relay circuit when a door is unlocked. 95 It is essential only that the switch 39 be opened when the door is unlocked.

The system of my invention is equally applicable to elevators which are operated by hydraulic motors and in Fig. 5 I have 100 shown one application of the system to such motors. The relay 38 in the local circuit operates the switch 39 or other means for alternately rendering the motor operative or inoperative. In the present embodiment the 105 switch 39 controls a circuit containing solenoids 42 which are arranged to apply and release brakes 43 from a movable part 44 of the hydraulic motor. The connection between the door locks and the brakes is such that when a door is unlocked, the brakes grip the part 44 and when the door is locked, the brakes are released. 110

I claim:

1. The combination with an elevator shaft 115 having a plurality of doors, of a car in said shaft, a motor for moving the car, a circuit for said motor, a switch in said circuit, means arranged at each door for locking the door in the closed position, and means connecting all of said locks with said switch whereby the unlocking of any door opens the switch.

2. The combination with an elevator shaft 120 having a plurality of doors, of a car in said shaft, a motor for moving the car, a circuit for said motor, a switch in said circuit, means arranged at each door for locking the door in the closed position and 125 a wire operatively connecting said locks and 130

said switch whereby the unlocking of any door opens the switch.

3. The combination with an elevator shaft having a plurality of doors, of a car in said shaft, a motor for moving the car, a circuit for said motor, a switch in said circuit, means arranged at each door for locking the door in the closed position, a vertically movable wire connected to said switch and to said locking means, movement of the wire in one direction serving to open the switch and in the other direction to close the switch, unlocking the door serving to move the wire in the first direction and locking the door serving to move the wire in the second direction.

4. The combination with an elevator shaft having a plurality of doors, of a car in said shaft, a motor for moving the car, a circuit for said motor, a switch in said circuit, a lock arranged at each door for locking the door in the closed position, a vertical wire arranged in the shaft, a lever connected to each lock and engaging said wire and arranged to move as the door is locked and unlocked, movement of said wire serving to close and open the switch.

5. The combination with an elevator shaft having a plurality of doors, of a car in said shaft, a motor for moving the car, a circuit for said motor, a switch in said circuit, a vertical wire arranged in said shaft and operatively connected to said switch, vertical movement of the wire serving to open and close the switch, a lock arranged at each door, means connecting each lock with the wire whereby operation of the lock is accompanied by a vertical movement of the wire.

6. The combination with an elevator shaft having a plurality of doors, of a car in said shaft, a motor for moving the car, a circuit for said motor, a switch in said circuit, a vertical wire arranged in the shaft and connected to said switch, vertical movement of the wire operating to open and close the switch, a lock arranged at each door, a lever projecting from said lock, said levers being provided with apertures through which the wire passes, a stop on the wire above each lever, the unlocking of the door being accompanied by an upward movement of the lever, means for locking the lever in its raised position and a bolt 55 on the door arranged to engage said door lock and simultaneously open said lever lock.

7. The combination with an elevator shaft having a plurality of doors, of a car in said shaft, a motor for moving the car, a circuit for said motor, a switch in said circuit, a vertical wire arranged in the shaft and connected to said switch, vertical movement of the wire operating to

open and close the switch, a lock arranged 65 at each door, a lever projecting from said lock, said levers being provided with apertures through which the wire passes, a stop on the wire above each lever, the unlocking of the door being accompanied by an upward movement of the lever, a latch arranged to engage and hold the lever in the raised position, a bolt on the door adapted to be engaged by the lock, said latch being so disposed that it is disengaged from the 75 lever by said bolt.

8. The combination with an elevator shaft having a plurality of doors, of a lock for each door, a car in said shaft, a motor for moving said car, a vertically movable 80 wire in the shaft operatively connected to each lock so that the unlocking of any lock moves the wire vertically, and means for preventing vertical movement of the wire.

9. The combination with an elevator 85 shaft having a plurality of doors, of a lock for each door, a car in said shaft, a motor for moving said car, a vertically movable wire in the shaft operatively connected to each lock so that the unlocking of any lock 90 moves the wire vertically, and means for holding said wire against movement while the car is in motion.

10. The combination with an elevator shaft having a plurality of doors, of a lock 95 for each door, a car in said shaft; a motor for moving said car, a vertically movable wire in the shaft operatively connected to each lock so that the unlocking of any lock moves the wire vertically, and means for 100 holding said wire against movement while the said motor is in operation.

11. The combination with an elevator shaft having a plurality of doors, of a lock for each door, a car in said shaft, a motor 105 for moving said car, a circuit for said motor, a vertically movable wire in said shaft operatively connected to each lock so that the unlocking of any lock is accompanied by a vertical movement of the wire, means 110 for locking the wire against movement and means connected to the motor circuit for operating said wire locking means.

12. The combination with an elevator shaft having a plurality of doors, of a lock 115 for each door, a vertically movable wire in said shaft connected to said locks whereby the unlocking of any lock is accompanied by a vertical movement of the wire and means for holding said wire against such 120 vertical movement.

13. The combination with an elevator shaft having a plurality of doors, of a lock for each door, a car in said shaft, a motor for moving said car, a circuit for the motor, a switch in said circuit, a vertically 125 movable wire in said shaft operatively connected to said locks so that the unlocking of

any lock is accompanied by a vertical movement of the wire, means operative during the operation of the motor for holding said wire against vertical movement, and
5 means operative by the vertical movement of the wire for opening the switch in the motor circuit.

In testimony whereof, I have hereunto set my hand at San Francisco, California, this 11th day of March, 1919.

HORATIO C. RANDALL.

In presence of—
H. G. PROST.
